CONVEYING PULVERULENT MATERIAL

Mikael Vogel-Jorgensen, Copenhagen, Denmark,
assignor to F. L. Smidh & Co., New York, N. Y.,
a corporation of New Jersey

Application June 22, 1935, Serial No. 27,877
In Great Britain July 6, 1934

5 Claims. (Cl. 302—36)

In Letters Patent of the United States No. 1,937,040, granted November 28, 1933 to the assignee herein upon the application of the present applicant, there is shown and described an apparatus for the conveying of pulverulent or granular material which in the mass is more or less fluent, such as cement raw meal, cement, pulverized coal and the like, in which a fluid under pressure, such as compressed air, is relied upon as the means by which movement of the material through a conduit is effected. When the material to be so conveyed is taken directly from the manufacturing apparatus or from a container in which it is stored and is fed into the conveying conduit there is a tendency of the compressed air or other motive fluid to escape back through the feeding mechanism. In the apparatus shown in said patent it was sought to prevent such escape of air or other fluid by compacting the material in the path of such possible escape of the air. The apparatus of the patent is effective to a degree in reducing the escape of air but for the handling of some classes of material it has been found desirable to provide means whereby the escape of air can be more effectively prevented. The apparatus of the present invention is generally similar to that shown in the patent, although modified in form, a valve or valves being provided in relation to the other parts of the apparatus and relied upon to prevent the escape of air in place of the means for compacting the material. Such valve, which may have different forms, yields to permit passage of the material from the rotating body into the chamber of the housing into which the motive fluid is admitted to provide the fluid pressure by which the material is moved on through the connected conveying conduit and closes upon the rotating hollow body when the pressure within the housing exceeds the pressure developed by the material under the influence of centrifugal force.

In the drawing, in which several different embodiments of the invention are illustrated—

Figure 1 is a view in longitudinal, central section of one embodiment of the invention, a worm conveyor being shown as a means to supply the material from the hopper to the hollow rotating body.

Figure 2 is a similar view of a different embodiment of the invention in which the movement of the material to the hollow rotating body is effected by a pressure differential.

Figure 3 is a view in diametrical section of another form of the hollow rotating body in which hollow arms are extended from the central portion.

Figure 4 is a view in transverse section on the plane indicated by the broken line 4—4 of Figure 3.

Figure 5 is a view generally similar to Figure 3, but showing a slightly different form of valve.

In the form of apparatus shown in Figure 1 the housing 20, somewhat lenticular in axial section and generally circular in transverse section, has connected thereto at one point a conduit 1 through which the material is conveyed from the housing to the point of deposit. At another point of the housing there is connected the supply of compressed air or other fluid under pressure sufficiently represented by the pipe 2. The material to be conveyed is in this instance assumed to be placed in a hopper 4 from which it is fed by a worm conveyor 3 to the interior of a hollow rotary body 5, lenticular in shape, having at one side a dished wall 6 and at the other side a plane wall 7. In this embodiment of the invention an annular valve 8, of rubber or other flexible material, is secured at its inner edge to the wall 7 and may bear, at its free outer edge, against the wall 6 of the rotating hollow body. In this instance the worm conveyor 3 is shown as rotated through a pulley 9 and the hollow body 5 is shown as carried by a shaft 10* which may be rotated through a pulley 10. It will be understood that, although the valve 8 may hang loosely when the apparatus is at rest, it will be caused by rapid rotation of the hollow body to which it is secured to stand at right angles thereto and that its outer edge will then lie in close contact with the lip of the wall 6 of the hollow body. It will also be understood that the pressure of the motive fluid within the housing 20 presses the valve against the wall 6 of the hollow body and effectually prevents the escape of air from the chamber of the housing 20 into the hollow body and so prevents the escape of the air through the feed device. Under the influence of the centrifugal force developed by the rotation of the hollow body the material within the hollow body will be caused to move outward between the valve 8 and the wall 6 into the chamber of the housing 20 from which it will be caused to move by the pressure of the compressed air within such chamber outward through the conveying conduit 1. Packing glands 11 and 12 may be provided as shown.

In the form of the apparatus shown in Figure 2 the housing 20, generally similar in shape to the housing shown in Figure 1, has connected thereto a conveying conduit 1 for the delivery of the material and a source of air under pressure, indicated at 2. In this instance, the rotating

hollow body 5^a is generally shaped like that shown in Figure 1, having a dished wall 6^a and at the other side a wall 7^a. The material in this instance is fed to the interior of the hollow rotating body 5 through a pipe 13 under the influence of pressure differential which may be established by suction through the hollow shaft 15 by any suitable means. The hollow body is in this instance carried by the shaft 15 to which a driving pulley 10^x may be applied. Between the walls 6^a and 7^a and, it may be, carried by and with the wall 7^a, there is provided a transverse wall or partition 14 to prevent the material being drawn into the hollow shaft 15 through the port 16 which communicates with the interior of the pipe 13. The partition 14 may also be provided with vanes 17 to assist in throwing the material which passes from the end of the pipe 13 outward into the hollow body under the influence of the centrifugal force developed by the rotation of the body. In this instance the valve 8^a may be of the same general character as that provided for the construction shown in Figure 1, being somewhat narrower by reason of the greater diameter of the fixed wall 7^a, but bearing at its outer edge, as before, against the wall 6^a at or near its edge. The operation of this form of apparatus is the same as that already described with respect to Figure 1 and need not be further explained herein.

While in the construction shown in Figures 3 and 4 the hollow body 5^b is rotated through the shaft 10^b and is connected through its hollow hub 5^c with the source of supply of the material it is shown in this instance as formed with four radiating hollow arms 18 extended from the central space, each of such arms being shown as provided at its end with a rigid valve 19 pivoted at 20 and having a counterweight 21 to control its action. It will be understood that the rotating hollow body is placed within a suitably shaped housing which it is not necessary to show since it functions in the same manner as does the housing shown in Figures 1 and 2.

The construction of the rotating hollow body 5^d, shown in Figure 5, is substantially the same as that of the rotating hollow body shown in Figures 3 and 4, mounted on a rotating shaft 10^d and communicating with the source of supply of material through the hollow hub 5^e. In this instance each valve 22 is shown as shaped to coact with the end of the arm 18^d to which it is applied, the valve being pivotally mounted, as at 20^d, and provided with an adjustable counterweight 21^d. The valves 22 are shaped as shown for the purpose of facilitating the distribution of the material as it

passes from the hollow rotating body into the chamber of the housing within which, as before, the hollow rotating body is placed.

It will be understood that various changes in details of construction and arrangement can be made to suit different conditions of use and, except as pointed out in the accompanying claims, the invention is not restricted to any of the particular constructions shown and described herein.

I claim as my invention:

1. In an apparatus for conveying pulverulent material, the combination of a housing, a conveying conduit connected to the housing, means to supply fluid under pressure to the housing, a hollow body mounted within the housing, means to rotate the hollow body, means to supply the material to the hollow body at the central portion thereof, and a valve applied at the outer edge of the hollow body and adapted to yield outwardly under the influence of the pressure developed by centrifugal action on the material within the hollow body and to be moved to closed position by pressure in the chamber of the hollow body.

2. In an apparatus for conveying pulverulent material, the combination of a housing, a conveying conduit connected to the housing, means to supply fluid under pressure to the housing, a hollow body mounted within the housing and having opposite walls, a valve carried by one of the walls and adapted to cooperate with the other wall to prevent the escape of air from the chamber of the housing, means to rotate the hollow body, and means to supply material to the hollow body at the central portion thereof.

3. An apparatus as described in claim 1, and in which the hollow body is mounted on a hollow shaft communicating with the interior of the hollow body and in which a pressure differential is maintained, and a transverse wall is placed within the hollow body to prevent the material being drawn into the hollow shaft.

4. An apparatus as described in claim 1, and in which an annular space is left between the edges of the two walls and an annular flexible valve is secured at its inner edge to one of the walls to cooperate at its outer edge with the other of the walls.

5. An apparatus as described in claim 1, and in which the hollow body is formed with radiating hollow arms with openings at their outer ends and in which valves yielding outwardly to pressure within the hollow body and inwardly to pressure within the chamber of the housing are provided at the ends of the hollow arms.

MIKAEL VOGEL-JORGENSEN.
